UNITED STATES PATENT OFFICE.

JOSEPH M. NARSH, OF COWEN, WEST VIRGINIA.

DESIGN FOR A HAME-IRON.

SPECIFICATION forming part of Design No. 27,076, dated May 18, 1897.

Application filed April 2, 1897. Serial No. 630,486. Term of patent 14 years.

To all whom it may concern:

Be it known that I, JOSEPH M. NARSH, a citizen of the United States, residing at Cowen, in the county of Webster and State of West Virginia, have invented and produced a certain new and original Design for Hame-Irons; and I do declare the following to be a full, clear, and exact description of the invention, such as will enable others skilled in the art to 10 which it appertains to make and use the same.

My invention relates to a new and original design for a hame-iron; and it consists of a hame-iron of the configuration and ornamentation shown in the accompanying drawings, 15 in which—

The leading features of my design consist in a strip curved longitudinally and provided 20 on one side with a semispherical shell 2, cut away to form curved fingers 3, which are triangular in cross-section. The upper ends of this shell are in the form of ears and have perforations therein as well as a curved guide- 25 flange 4, which extends partially about and is parallel with a portion of the ears.

What I claim is—

The design for a hame-iron, as herein shown and described. 30

In testimony whereof I hereunto affix my signature in presence of two witnesses.

JOSEPH M. NARSH.
